PADDING FOR DRY CLEANER STEAM PRESSES

Charles G. Young, San Mateo, and Elmer C. Hol-
ler, San Francisco, Calif., assignors to Patek &
Co., San Francisco, Calif., a corporation of Cali-
fornia

Application November 21, 1949, Serial No. 128,571

8 Claims. (Cl. 38—66)

1

This invention relates to press padding, and more particularly to padding adapted for covering dry cleaner steam buck presses, such as those employed for the pressing of suits or other similar cloth articles.

In the pressing of articles on dry cleaner steam buck presses, particularly in commercial establishments, the padding employed on the press buck is very important in determining the quality of work. To effect smooth finished work without wrinkles or impressions and free from shine, it is important that the padding have a proper degree of resiliency. At the same time, for reasons of economy, it is desirable that the padding be of such material as to maintain its resiliency over a long time and be able to withstand the moisture and the relatively high temperatures encountered in such steam pressing operations.

Material such as cotton, heretofore employed for the described purposes loses its resiliency and life fast, and consequently has to be renewed frequently. Furthermore, it does not provide all the resiliency desired, and as a result the finish of the pressed goods is often marred by wrinkles or impressions left by buttons or the like.

Summarizing this invention, it embodies the principle of construction which is disclosed and claimed generically in assignee's copending application, Serial No. 128,572, filed November 21, 1949, by the same inventors, for "Padding for Presses or the like." As is pointed out in such application, the padding comprises an inner flannel layer of highly heat, moisture and steam resistant, and resilient synthetic fiber having a nap side facing outwardly, preferably in the form of relatively thick double faced flannel (i. e., a combed out nap on each face or side extending from an intermediate woven portion), a layer of like material in the form of a single faced flannel (i. e., a combed out nap on only one face or side extending from an exposed woven portion) overlying the inner flannel layer with the exposed woven face or side, or in other words the uncombed face of the single faced flannel, outermost and its nap side facing the nap side of the inner layer, and a finely woven relatively thin smooth finished cover of the same material over the single faced flannel.

For the particular purpose which the padding of the present invention is adapted, a relatively soft rubber layer, of preferably porous sponge rubber, is interposed between the double faced flannel and the single faced flannel to provide for added resiliency; and the sponge rubber layer and the double faced flannel are prefer-

2

ably secured together with an asbestos guard in the form of a composite laminated sheet, for ease of assembly.

All of the layers of the padding are tightly bound over the press buck to provide a smooth, highly resilient and heat and moisture resistant padding which because of such resiliency sets the creases in the pressed article without causing breakage of articles such as buttons or the like, without leaving impressions of such buttons, and enables the article to be pressed free from shine which otherwise results from too hard a supporting foundation for the article.

Nylon is the synthetic fibrous material which has been found most suitable for the described purpose, although any other synthetic fiber having the above described physical properties can be employed. So-called "rayon" fiber is not suitable because of its lack of heat resistance; and in this connection, the preferred nylon fiber should be virgin nylon, as regenerated nylon fiber is not heat resistant to the extent required in the pressing operation.

Referring to the drawings:

25 Fig. 1 is a perspective view of a press buck with portions of the padding of this invention lifted therefrom in exposed relationship to illustrate the construction;

30 Fig. 2 is an enlarged transverse vertical sectional view of the press buck and the padding thereof;

35 Figs. 3, 4, 5, and 6 provide an exploded view illustrating the padding structure with the elements thereof in the order on which they are arranged on the buck. In such figures:

35 Fig. 3 is a fragmentary vertical sectional perspective of the cover of the padding;

Fig. 4 is a fragmentary vertical sectional perspective of the outer single faced nylon flannel layer;

40 Fig. 5 is a fragmentary vertical sectional perspective of the composite laminated sheet comprising a lower asbestos sheet, the inner double faced flannel sheet, and an overlying sponge rubber sheet, all suitably secured together;

45 Fig. 6 is a fragmentary vertical sectional perspective of a wire screen which is placed over the buck.

In Figures 1 and 2 are shown a conventional metal steam buck 2 having perforations 3 through 50 which the steam is ejected, and a vacuum on the goods being pressed is effected in accordance with the well known operation of this type of steam buck pressing machine. Over the top of the buck is placed a removably mounted metal screen 4 of copper or brass and of about 36 to

50 mesh, which is commonly employed on steam bucks for the purpose of diffusing the steam over the entire surface of the buck. It will be noted that this metal screen is of a configuration substantially congruent to the top of the buck so that it extends only over the area defined by perforations 3.

As is more clearly shown in Figs. 2 and 5, the first unit of the padding of the invention comprises a laminated sheet formed of an asbestos sheet 6 of relatively open weave, about 12 per inch, which is stitched by stitching 7 of virgin nylon fiber to an inner double faced virgin nylon flannel sheet 8, in turn adhesively united by any suitable heat and moisture resistant adhesive 9, such as latex cement, over the line of stitching 7 to a relatively thick layer 11 of relatively soft rubber, preferably porous sponge rubber of about $\frac{1}{2}$ inch thick. Stitching 7 extends all along and adjacent the edge of the double faced flannel layer 8. It is desirable that stitching 7 be of virgin nylon fiber because it enhances the life of the pad; as stitching of other fiber may not be able to withstand the moisture and the relatively high pressing temperatures.

It will be noted that asbestos sheet 6, which serves as a guard to protect the padding from scorching and also serves to radiate even flow of heat from the buck, is larger than sheets 8 and 11, so as to provide a free marginal edge portion 11' about its entire periphery to fit smoothly over the sides of the buck as shown in Fig. 2; while sheets 8 and 11 of the padding are substantially congruent and of a size, adapted to cover substantially the top of the buck. This provides for smoothness. The edge of the asbestos sheet 6 is piped with suitable piping 12 to prevent fraying; and as this piping is not subjected to the extensive heat from the steam of the buck, it may be of cotton.

The preferred double faced inner flannel sheet 8 provides a desirable element of the padding in obtaining the desired resiliency, and as is well known it consists of an intermediate woven portion 13 with a nap 13' combed out from each side or face thereof. Although such double faced flannel is desirable for enhanced resiliency, it may be formed of a pair or even more of single faced flannel sheets of the material described, arranged so that a nap side will face outwardly as is the case with respect to the double faced flannel layer.

Sponge rubber layer 11 provides added resiliency which is important in obtaining a smooth finish on the goods, and is of any suitable type adapted to withstand the heat and moisture encountered in the press. In this connection, the virgin nylon material employed is particularly capable of withstanding such heat and moisture, thus making for long life, and at the same time obviating soggy padding which impedes the pressing operation. The composite laminated sheet may be made as separate sheets but the formation of a unitary sheet of the character described, provides ease of assembly thereof on the steam buck, and is, therefore, preferred.

A next important element of the padding resides in single faced virgin nylon flannel sheet 14 of substantially the same size as double faced nylon sheet 8 and sponge rubber sheet 11 so as to fit congruently thereover free of attachment thereto. Single faced flannel sheet 14 has a nap side 16 combed out only along one side so that the opposite side provides a relatively fine exposed weave 15. In laying sheet 14 over the com-

posite or laminated sheet, it is important that the nap side 16 be faced inwardly toward an outwardly facing nap on one side of the double faced flannel sheet 8, with the finely woven smooth side 15 of sheet 14 outermost. Such arrangement provides a smooth finish at the top to enhance smoothness of pressing; and at the same time enhances the resiliency which is provided by the facing nap sides 13' and 16 and the interposed rubber layer 11, such resiliency being important for the pressing operation. In this connection, although opposed nap sides 13' and 16 will provide the requisite resiliency in many pressing operations, the interposed rubber layer 11 is desirable for steam bucks because of the high pressures encountered in such type of machine. It is preferred to place the rubber layer 11 between the synthetic fibrous sheets to shield such rubber from the direct action of the steam. Single faced flannel sheet 14 could be secured to the previously described laminated sheet to provide a composite unit therewith, but it is preferred not to do so to avoid any lumps that might occur in such securing. Also, in wear of the padding, the single faced flannel sheet 14 should it wear out first, can be more readily replaced.

The flannel sheets may be of any suitable weight available on the market. Most desirable weights range from 10 oz. to 33 oz. per square yard.

For all practical purposes, a single layer 8 of the double faced flannel and a single layer 14 of the single faced flannel will suffice. However, more than one layer of each of these materials may be employed for added resiliency. In such event, it is important that the relatively smooth finely woven side 15 of the overlying single faced flannel be outermost to obtain the requisite smoothness, and that a nap side of the inner flannel layer face outwardly.

The final element of the padding of the invention consists of a cover sheet 17, also of virgin nylon material and which has only a relatively fine weave so that both sides thereof have a relatively smooth finish. Such weave is preferably a twill weave but it may be a plain weave or any other type of fine weave which will provide a smooth finish. A suitable weight for cover 17 is between 3 oz. to 7 oz. per sq. yard.

Cover sheet 17 is provided with a skirt portion 18 adapted to fit around the sides of the buck. Adjacent its outer edge, skirt portion 18 is provided with a hem 19 in which may be a draw string 21, thus providing means for securing the entire padding tightly to the buck. If desired, springs 22 may be connected between opposite portions of the hem to enhance securing of the cover, and a metal rod or the like can be used to which the springs may be connected.

Skirt portion 18 could be made of the same material as the remainder of the cover 17 but it is preferred to employ cotton as the material for the skirt, stitched to the nylon top of cover 17. This is so because cotton is more flexible than the nylon, and when the skirt is tightened about the buck, it therefore provides better hugging qualities, thus obviating possible wrinkle formation in the top of the cover.

From the preceding description, it is seen that the padding of my invention provides extreme resiliency to effect smooth pressing, and at the same time it is sufficiently porous to permit effective penetration of the steam into the goods being pressed, and also efficacious functioning of the vacuum in the pressing operation. Because

of the high heat and moisture resistance of the material employed in the padding, it has the life of 30 to 35 times that of cotton padding heretofore employed for similar purposes. Therefore, although more expensive than cotton padding, it is more economical in the long run.

We claim:

1. Padding for a dry cleaner steam press comprising an inner layer of resilient and heat and moisture resistant synthetic fibrous material of flannel having a nap side facing outwardly, a relatively soft rubber layer over said inner flannel layer, a layer of single faced flannel of said synthetic fibrous material over said rubber layer, and a relatively finely woven cover of said synthetic fibrous material.

2. Padding for a dry cleaner steam press comprising an inner layer of resilient and heat and moisture resistant synthetic fibrous material of flannel having a nap side facing outwardly, a relatively soft rubber layer over said inner flannel layer, a layer of single faced flannel of said synthetic fibrous material over said rubber layer having its nap side facing said inner layer and its woven side outermost with respect to said inner layer, and a relatively finely woven cover of said synthetic fibrous material.

3. Padding for a dry cleaner steam press comprising an asbestos guard sheet adapted to overlie the press buck, an inner layer of nylon flannel over said asbestos guard sheet, a relatively soft rubber layer over said inner flannel layer, a layer of single faced nylon flannel over said rubber layer having its nap side facing said inner layer and its woven side outermost with respect to said inner layer, and a relatively finely woven nylon cover.

4. Padding for a dry cleaner steam press comprising an asbestos guard sheet adapted to overlie the top and the sides of a press buck, an inner layer of nylon flannel over and secured to said asbestos guard sheet, said inner flannel layer being of smaller size than said asbestos guard sheet to provide a free marginal edge portion about the entire periphery of said asbestos guard sheet which portion is adapted to extend over the sides of the buck, a relatively soft rubber layer congruent to and over said inner flannel layer and secured to said inner flannel layer,

a layer of single faced nylon flannel congruent to and over said rubber layer having its nap side facing said inner layer and its woven side outermost with respect to said inner layer, and a relatively finely woven nylon cover.

5. Padding for a dry cleaner steam press comprising an asbestos guard sheet adapted to overlie the top and the sides of a press buck, an inner layer of double faced nylon flannel over and stitched to said asbestos guard sheet all along and adjacent the edge of said double faced flannel layer, said double faced flannel layer being of smaller size than said asbestos guard sheet to provide a free marginal edge portion about the entire periphery of said asbestos guard sheet which portion is adapted to extend over the sides of the buck, a relatively soft rubber layer congruent to and over said double faced flannel layer and adhesively united to said double faced layer along the line of stitching between said double faced layer and said asbestos guard sheet, a layer of single faced nylon flannel congruent to and over said rubber layer free of attachment therewith and having its nap side facing said double faced layer and its woven side outermost with respect to said double faced layer, and a relatively finely woven nylon cover.

6. The construction of claim 5 including a perforated metal screen adapted to underlie the asbestos guard sheet.

7. The construction of claim 5 in which the nylon cover is provided with a skirt portion adapted to overlie the sides of the buck and provide a means for securing the padding to said buck.

8. The construction of claim 7 in which said skirt portion is of cotton.
